UNITED STATES PATENT OFFICE.

ABNER JUDSON LURRY, OF BATON ROUGE, LOUISIANA.

PRESS-CLOTH-REPAIRING MACHINE.

1,396,644.

Specification of Letters Patent.

Patented Nov. 8, 1921.

Application filed January 14, 1921. Serial No. 437,295.

To all whom it may concern:

Be it known that I, ABNER JUDSON LURRY, a citizen of the United States, residing at Baton Rouge, in the parish of East Baton Rouge and State of Louisiana, have invented certain new and useful Improvements in Press-Cloth-Repairing Machines; and I do hereby declare the following to be a full, clear, and exact description of the invention, such as will enable others skilled in the art to which it appertains to make and use the same.

The present invention relates to improvements in press cloth repairing machines, and has for an object to provide an improved machine for the rapid and effective repairing, lacing, or darning of fabric known as press cloth, which is a kind of material used for the wrapping of oleaginous products while undergoing compression in hydraulic presses, to the action of which such products are subjected for the purpose of expelling the oil therefrom.

This press cloth becomes torn and rent in places which renders it unfit for effective use, and which makes it difficult to handle involving waste of time and labor.

It is an object of the invention, therefore, to provide an improved machine in which this press cloth may be repaired at the mill quickly and at a minimum of expense, while providing for the convenience of the operator and for his personal comfort during the repairing operation.

The invention moreover aims to provide a machine for carrying out the above objects, which will be simple in construction and inexpensive to manufacture, and which will be adjustable with respect to a seat provided for the operator.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a view in side elevation of an improved press cloth repairing machine constructed according to the present invention;

Fig. 2 is a top plan view of the same;

Fig. 3 is an end view of the machine;

Fig. 4 is a sectional view taken on the line 4-4 in Fig. 2;

Fig. 5 is a longitudinal sectional view taken on the line 5-5 in Fig. 4;

Fig. 6 is a plan view of one of the movable jaws;

Fig. 7 is a longitudinal edge view of the same;

Fig. 8 is a view in elevation of one of the movable jaw holders; and

Fig. 9 is an elevational view of one of the fixed jaws.

Referring more particularly to the drawings, according to the invention I provide a support which preferably takes the form of a carpenter's saw bench made up of supporting legs 1 and a pair of beams 2 and 3 fixed to the legs and extending in a substantially horizontal direction with a slot 4 left between them. A seat 5 for the operator is either fixedly or adjustably secured upon the support, which is constructed preferably near one end thereof so as to leave ample space on the support for the clamping device, which is of a duplex character.

The clamping device consists of a pair of heads 5 and 6 made, as shown in Figs. 3 and 4, of a substantially diamond shape in elevation and provided with legs 7 adapted to receive bolts 8 which extend through the slot 4 of the support and are adjustable therein. Clamping nuts 9 on the ends of the bolts are adapted to secure the device in the adjusted position on the support. In this way the clamping device may be moved toward or from the seat 5 to accommodate the operator.

A trough beam 10 having divergent side walls is mounted upon the central and uppermost portions of the heads 5 and 6 and extends between them lying substantially parallel with the beams 2 and 3 of the support. This trough beam may be secured to the heads 5 and 6 in any suitable manner, bolts 11 being indicated as this method of fastening renders it possible to disassemble the machine.

In the trough beam is supported a saddle 12 preferably made of wood and having a rounded upper surface to receive the broken or rent portion of the piece of press cloth. Adjacent portions of the cloth adjoining the broken portion are received at opposite sides of the saddle between pairs of fixed and

movable jaws which clamp it securely in place and prevent the cloth at the opposite sides of the rent from falling away. The fixed jaws are indicated at 13 and 14, and 5 they are supported in convergent relation at opposite sides of the saddle. One of the jaws 13 is shown more particularly in Figs. 5 and 9, where these jaws are illustrated to be provided with supporting arms 15 and 10 16 formed with angularly disposed bearing bosses 17 and 18 for coöoperating with similar complementary bearing bosses 19 and 20 carried by the opposite heads 5 and 6.

The bearings thus provided are adapted 15 to receive rock shafts 21 and 22 which carry collars 23 secured thereon by set screws 24 and which hold the shafts in place at one end by thrust of the collars 23 against the bearing bosses 17 and 19. The shaft 21 is 20 provided at its other end with a set collar 25 having an actuating handle 26, while in a similar manner the shaft 22 carries a set collar 27 having an actuating handle 28. The set collars encounter the bearing bosses 25 18 and 20 and prevent longitudinal displacement of the shafts.

The movable jaws are indicated at 29 and 30, one such jaw being shown in Figs. 6 and 7. The upper face of each jaw is provided 30 with corrugations 31 and with bolt holes 32 near its longitudinal central portion. Recesses 33 are cut in the sides of the movable jaw also preferably near the longitudinal center thereof, the under sides of the jaw 35 being cut away as indicated at 34. The movable jaw 30 is adapted to be removably received in a holder 35 shown more particularly in Fig. 8 provided with upstanding lugs 36 slidably receivable in the recesses 40 33 in the jaw and having bolt holes 37 in which to receive the fastenings which pass through the bolt holes 32 of the jaw.

A slot 38 is made in the web 39 of the holder to receive the shaft 22 and to permit 45 the holder to slide at right angles to the axis of the shaft while permitting the shaft to rotate freely in the holder. An eccentric strap 40 projects outwardly from the holder and forms therewith a recess in which the 50 eccentric is housed. As more particularly shown in Fig. 4, the eccentrics 41 and 42 operate within the housing thus formed and act to shift the movable jaws 29 and 30 toward and away from the fixed jaws 14 and 55 13 respectively.

A set collar 43 on each of the shafts is fitted up against the eccentric and holds the same in the housing provided by the holder.

A second set collar 44 on the opposite side 60 of each shaft provides an abutment against which one end of a coil spring 45 seats, the other end pressing against a washer 46 and urging said washer against the holder so as to resist turning of the shafts which results 65 in the shafts being thus yieldingly held in

adjusted position. These parts 44, 45 and 46 are also for the purpose of causing the two ends of the movable jaw to be equally spaced from the stationary jaw, when open, and on the other hand to permit the movable 70 jaw to adjust itself against any unevenness of the material when under pressure.

Plates 47 and 48 are secured to the lower sides of the arms 15 and 16 of the stationary jaws and are spaced from the jaws at their 75 upper ends in order to provide slots 49 shown in Figs. 4 and 9 in which to permit passage of the cloth.

In the use of the device, the operator seats himself upon the seat 5 with one leg to each 80 side of the beams 2 and 3. He then draws the clamping device toward him until it is at a convenient position at which time the nuts 9 may be tightened to secure it in place. Opposite ends of the cloth to be darned or 85 laced are threaded through the spaces between the two sets of clamping jaws, while these jaws are open and the ends are brought together substantially upon the middle high portion of the wooden saddle 12. 90

The cloth is then clamped within the jaws which will hold it in proper position. An awl is used to punch holes through the cloth at opposite sides of the meeting edges and a needle with thread is inserted in the opposite direction through the holes made by the awl, preferably before the awl is withdrawn so as to facilitate this operation. 95

The machine affords the operator the opportunity to firmly hold the work in a position that will enable him to adjust himself to the work in the fashion of a shoemaker with the work strapped to his knee, or the tailor pinning it to his pants near the knee and to this end the arrangement and disposition relatively of the seat and the clamping device is such that the work will fit as closely as possible in the lap of the operator, and it will permit the operator to move his legs as closely as possible together and about 100 the machine so as to prevent fatigue and, at the same time, to allow the cloth ends to pass freely outside of the legs. 105

The movable jaws 29 and 30 are opened by swinging the handles 26 and 28 over 115 toward one another until they strike the opposite shafts or adjacent parts, the handles then being crossed. After the material is placed in the device, the levers are swung in an opposite direction, which moves the eccentric to the position shown at the left in Fig. 4 thereby clamping the material between the jaws. 120

The device is useful, not only in securing pieces of cloth together, but also in darning 125 holes in cloth and securing rents of every description.

It is obvious that various changes and modifications may be made in the details of construction and design of the above specifi- 130

cally described embodiment of this invention without departing from the spirit thereof, such changes and modifications being restricted only by the scope of the following 5 claims.

What is claimed is:

1. A device of the kind described comprising a support, fixed jaws associated therewith, movable jaws coöperating with the fixed jaws, holders for the movable jaws, formed with eccentric straps, eccentrics movable in said straps, rock shafts for moving said eccentrics, and handles on said rock shafts, substantially as described. 10
2. A device of the kind described comprising a support for the cloth, fixed jaws associated therewith, a movable jaw coöperating with each fixed jaw, a holder for detachably receiving each movable jaw, said holder having an eccentric strap, a rock shaft passing through said holder, an eccentric on said shaft engaging the strap, and yieldable means for securing the holder in adjusted position, substantially as described. 15
3. A device of the kind described comprising a seat, a support therefor, a cloth repairing device comprising a pair of heads, means for adjustably securing said heads to the support, a cloth support carried by said heads, fixed jaws extending between said heads at opposite sides of the cloth support, movable jaws beneath the fixed jaws, and means for actuating said movable jaws, substantially as described. 20
4. A device of the kind described comprising a seat, a support therefor having a slot, a cloth repairing device comprising a pair of spaced apart heads, clamping means for the heads fitting in the slot in said support and being adjustable therein, a trough beam extending between said heads at the upper central portion thereof, a wooden saddle supported in said trough beam, a pair of fixed jaws secured to the heads and lying at opposite sides of said saddle, said 40 fixed jaws being arranged in divergent relation, movable jaws beneath the fixed jaws, and means for shifting said movable jaws toward and from the fixed jaws, substantially as described. 45
5. A device of the kind specified comprising a pair of heads, a trough beam connected between the heads at substantially the central portions thereof, a saddle placed removably in said beam, movable jaws lying at an inclination downwardly at the sides of said beam for receiving the cloth therefrom, fixed jaws coöperating with said movable jaws, and means to reciprocate the movable jaws, substantially as described. 50
6. A device of the kind described comprising a pair of spaced apart heads, a saddle removably supported between said heads at their highest and intermediate portion, the heads sloping off downwardly at opposite 55 diagonal inclinations, fixed jaws arranged upon the heads and extending between the heads at the same inclination as the side portions thereof, and coöperating movable jaws adapted to shift back and forth with respect to the fixed jaws to clamp the cloth therebetween, substantially as described. 60

ABNER JUDSON LURRY.
